EX
OR D 21,003 DESIGN.

A. PETZOLD.
TABLE COVER OR CURTAIN.

No. 21,003.

Patented Aug. 18, 1891.

UNITED STATES PATENT OFFICE.

ADOLPH PETZOLD, OF PHILADELPHIA, PENNSYLVANIA, ASSIGNOR TO JOHN BROMLEY & SONS.

DESIGN FOR A TABLE-COVER OR CURTAIN.

SPECIFICATION forming part of Design No. 21,003, dated August 18, 1891.

Application filed January 30, 1891. Serial No. 379,703. Term of patent 3½ years.

To all whom it may concern:

Be it known that I, ADOLPH PETZOLD, a citizen of the United States of America, residing at Philadelphia, in the county of Philadelphia

and State of Pennsylvania, have invented a certain new and original Design for a Table-Cover or Curtain, of which the following is a specification, reference being had therein to the accompanying drawing.

My invention relates to the surface ornamentation of a table-cover or curtain, usually applied to a woven chenille fabric; and it consists of the design therefor illustrated in the accompanying photographic drawing, its leading features being the outer border A A', the

field-center B, containing ornamental figures, as shown. At either or both ends within the border-spaces may be added the supplemental ornamentation A².

I claim as my invention.

1. The design for a table-cover or curtain, substantially as shown and set forth.
2. The design for the border A A', substantially as shown and set forth.

In testimony whereof I affix my signature in presence of two witnesses.

ADOLPH PETZOLD.

Witnesses:

JULIUS PEGEL,
EDWARD BROMLEY.
